UNITED STATES PATENT OFFICE.

GUSTAVO GERMANI, OF PITTSBURG, PENNSYLVANIA, ASSIGNOR OF ONE-HALF TO RAFFAELE ZANGRILLI, OF PITTSBURG, PENNSYLVANIA.

SPARKING MECHANISM FOR EXPLOSIVE-ENGINES.

No. 927,346.

Specification of Letters Patent.

Patented July 6, 1909.

Application filed September 8, 1908. Serial No. 452,099.

To all whom it may concern:

Be it known that I, GUSTAVO GERMANI, a citizen of the Kingdom of Italy, residing at Pittsburg, in the county of Allegheny and State of Pennsylvania, have invented certain new and useful Improvements in Sparking Mechanism for Explosive-Engines, of which the following is a specification, reference being had therein to the accompanying drawing.

10 My invention refers to improvements in sparking mechanism for explosive engines, as gas or oil engines, and it has for its object to provide means whereby an initial ignition may be provided by manual operation 15 through a generator actuated by any suitable means as for instance the ordinary crank employed for starting the engine shaft, or any suitable hand-operated mechanism; with means for coupling the generator automatically with the motor shaft and for automatically uncoupling from the preliminary actuator, so as to produce continuous generation 20 of current and a resulting spark during the operation of the motor, as shall be more 25 fully hereinafter described.

In the drawings:—Figure 1 represents a diagrammatic arrangement of the apparatus, in plan. Fig. 2 is a detail in elevation, partly in section of one of the driven wheels for the 30 generator shaft. Fig. 3 is a cross sectional view on the line III. III. of Fig. 2.

In carrying out my invention I propose to employ any suitable generator as a dynamo 2 connected by suitable conductors with the 35 spark plug of an engine or motor 3 as will be readily understood, and for the purpose of continuously driving the generator during the running of the motor, the generator shaft 4 is geared with motor shaft 5 by belt or other 40 suitable connecting means 6 running from driven wheel 7 to driving wheel 8. Mounted on generator shaft 4 is a secondary hand-operated wheel 9 geared by belt or other means 10 with a hand-actuated wheel 11, 45 loosely mounted on motor shaft 5 concentric with wheel 8 and normally free thereof. The relative proportions of wheels 7 and 8 and 9 and 11 respectively to each other, are regulated by the speed of the actuating element, 50 i. e., motor or hand mechanism, so that the generator shaft 4 may be actuated at the desired speed to make a current producing spark. Hand-actuated wheel 11 is normally free on shaft 5 or an extension thereof and is 55 provided with an operating handle 12 of ordi-

nary construction for cranking and intermediate clutch mechanism 13, whereby the wheel 9 may be independently rotated and upon thrusting wheel 11 into gear with wheel 8 the motor shaft 5 may be “cranked” until 60 the motor is started, after which its shaft 5 will rotate independent of hand wheel 11. The detail construction of these parts may be designed to suit conditions by the designer of the mechanism and will be understood without further description.

Driven wheels 7 and 9 are so geared with generator shaft 4 that one or the other will, by interposed clutch mechanism, actuate the shaft and the armature of the generator, 70 but will become uncoupled from the shaft when the shaft rotates faster than said wheel. The object of this construction is that, during the preliminary sparking by hand, shaft 5 and shaft 4 may be rotated by hand-actuated wheel 11 and 9 respectively, power driven wheel 7 remaining unclutched, due to the fact that it rotates slower than wheel 9. Wheel 11, loosely mounted on shaft 5, 75 is thrust into clutch-engagement with wheel 8 (keyed to shaft 5) by clutch 13. Rotation of wheel 11 drives motor shaft 5 and its wheel 8, and also rotates both wheels 9 and 7 by their belts 10 and 6. Wheel 9 rotating faster than wheel 7, actuates shaft 4 and 80 produces the spark resulting from operation of wheel 11. Thereafter the motor will operate, due to the spark, driving its own shaft 5 and wheel 8 and 7, at increasing speed, whereupon wheel 9 will be automatically relieved, wheel 7 engaging shaft 4 by its clutch mechanism and wheel 8 running at a faster speed will become automatically uncoupled from wheel 11, the motor continuing 85 in the same manner until the spark is interrupted. The operation is dependent upon the automatic coupling and uncoupling mechanism of wheels 9 and 7 with shaft 4. In order to provide such automatic coupling and uncoupling mechanism, any suitable 90 means may be employed as ordinary ratchet gearing, but I have shown in the drawings a device employing a series of eccentrically mounted rollers or cams 14 mounted by their terminal bearing studs 15 in bearing plates 16, 16, at each side of the hub 17 of wheels 7 and 9, the construction being the same in each. By this arrangement as wheel 9 is rotated in the direction of the arrow, 95 Fig. 2, rollers 14 will grip against shaft 4 in 100 105 110

rotative engagement with it, rollers 14 of wheel 7 in the meantime being inoperative, actuating the generator until such time as the motor 3 commences to run, whereupon shaft 4 will be automatically gripped by the rollers 14 of wheel 7, and wheel 9 will become inoperative, coincident with the termination of the cranking operation.

The cams 14 are pivotally mounted by their terminal bearing studs 15 in the plates 16, which as shown in Fig. 2 are secured to the hubs 17 by screws or other suitable means. These plates 16 constitute the housings for the cam roller grips, and will 15 certainly and positively operate in the manner stated. That is to say, either wheel 9 or wheel 7 when rotating in the direction of the arrow Fig. 2, will positively grip the shaft 4, but when the shaft 4 is rotated 20 faster than either of said wheels 7 or 9, then such wheel will become uncoupled from the shaft automatically, due to the faster rotation of the shaft. It will also be seen that each wheel will, as actuated, rotate independently and shaft 4 will be automatically uncoupled from the other wheel without friction, or lost motion or any back action. It 25 will also be understood that any other means may be employed instead of the cranking 30 lever and its wheel 11, as in the case of an automatically starting motor, when the wheel 9 may be geared with any separate actuating hand-operated means.

The operation of the invention will be 35 readily understood by all those familiar with the construction and operation of explosive engines, as used with automobiles, motor boats, etc. It obviates the necessity of batteries and reduces the equipment and power 40 plant to a unitary minimum.

Having described the invention, what I claim is:—

1. Means for starting an explosive motor consisting of a generator, means embodying 45 cam grip mechanism for positively coupling said generator with the motor and for automatically uncoupling therefrom, independent actuating mechanism, and separate means embodying cam grip mechanism for 50 positively coupling the generator with said independent actuating mechanism, and for automatically uncoupling therefrom.

2. Means for starting an explosive motor consisting of a generator having a shaft, a 55 driving wheel fixedly secured to the motor shaft and gearing connecting said wheel with

a gripping wheel loosely mounted on the shaft of the generator for coupling said generator with the motor, and for uncoupling therefrom, an independent actuating wheel 60 and gearing connecting it with a gripping wheel loosely mounted on the generator shaft for coupling therewith and uncoupling therefrom, said generator shaft wheels having means for automatically uncoupling 65 either of said actuating wheels from the shaft upon independent positive rotation of the other wheel.

3. Means for starting an explosive motor having a shaft consisting of a generator having 70 a plurality of loosely mounted driving wheels and automatic locking and unlocking mechanism therefor, a driving wheel mounted on the motor shaft and geared with one of said wheels, a second wheel mounted for independent hand operation, and means for operatively connecting it with the motor-actuated wheel, substantially as set forth.

4. The combination with a motor and its 75 shaft and a generator and its shaft and connected sparking mechanism; of a plurality of wheels loosely mounted on the generator shaft provided with means for gripping said shaft in one direction and for being released therefrom when said shaft is rotated in the same direction, a driving wheel secured to the motor shaft having clutch mechanism and geared with one of said wheels, and an independent loosely mounted wheel provided with a crank and clutch mechanism, geared 80 with the other of said wheels, substantially as set forth.

5. The combination with a motor and its shaft and a generator and its shaft and connected 85 sparking mechanism; of a plurality of wheels loosely mounted on the generator shaft provided with gripping cams arranged to engage the shaft in one direction and to be released therefrom when said shaft is rotated in the same direction, a driving wheel secured 90 to the motor shaft having clutch mechanism and geared with one of said wheels, and an independent loosely mounted wheel provided with a crank and clutch mechanism, geared with the other of said wheels, substantially 95 as set forth.

In testimony whereof I affix my signature in presence of two witnesses.

GUSTAVO GERMANI.
